ATTACHMENT DEVICE FOR CYLINDER
BORING MACHINES

Olov J. E. Olsson, Minneapolis, Minn., assignor to
Storm Manufacturing Co., Inc., Minneapolis,
Minn., a corporation of Minnesota

Application December 14, 1944, Serial No. 568,155

9 Claims. (Cl. 77—2)

1

This invention has relation to an attachment device for cylinder boring machines.

An object of the invention is to provide an attachment device of novel and improved construction for fastening a cylinder boring machine upon a block having cylinders to be bored in fixed relation to the block and cylinders.

A further object is to provide an attachment device for fastening a cylinder boring machine upon a block having cylinders to be bored in fixed relation to the block and cylinders which will include various improved features and characteristics of construction novel both as individual entities of the attachment device and in combination with each other.

A further object is to provide an attachment device which will include a novel and improved construction and arrangement for anchoring and clamping a cylinder boring machine to and upon a block having cylinders to be bored.

And a further object is to provide a cylinder boring machine attachment device incorporating features and characteristics of construction as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and meant in no way in a limiting sense, changes in details of construction and arrangement of parts being permissible so long as within the spirit of the invention and the scope of the claims which follow.

In the accompanying drawings forming a part of this specification,

Fig. 1 is a top plan view of an attachment device made according to the invention, the view also disclosing, in transverse section taken as on line 1—1 in Fig. 3, the base of a cylinder boring machine with which the attachment device is assembled;

Fig. 2 is a transverse sectional view, taken as on line 2—2 in Fig. 1, of the cylinder boring machine base, disclosing parts of the attachment device in end elevation;

Fig. 3 is a longitudinal central sectional view, taken as on line 3—3 in Fig. 1; and

Fig. 4 is a detail sectional view, taken as on line 4—4 in Fig. 3.

With respect to the drawings and the numerals of reference thereon, 10 denotes the base of a cylinder boring machine having a boring tool (not shown) adapted to be operative upon

2

cylinders to be re-bored of a cylinder block 11. As disclosed, the cylinder boring machine base 10 is supported upon the cylinder block 11, and the attachment device of the invention is for removably securing said cylinder boring machine to said cylinder block at a cylinder 12 of the cylinder block other than a cylinder to be re-bored, according to practice which is usual, said block 11 of course including cylinders, not necessary to be shown, additional to the cylinder 12.

The cylinder boring machine base 10 includes spaced apart, parallel, upright walls, designated 13, 13, which provide a rectilinear area 14 between said walls 13, 13 open to the lower margin 15 of said base 10.

An anchor, designated 16, of the attachment device is adapted to be situated within a cylinder, such as 12, of a cylinder block, such as 11, adjacent a cylinder to be re-bored, a clamp, represented at 17, of said attachment device is adapted to be situated within the rectilinear open area 14 of the base, such as 10, of a cylinder boring machine and above said cylinder block, and a connector, denoted 18, of the attachment device is for interconnecting the anchor 16 and the clamp 17.

An upper entity of the anchor 16 is constituted as a block of metal or material providing a vertical slab 19, a horizontal ledge 20 integral with an upper portion of said vertical slab 19, and spaced, parallel ears 21, 21 situated at the inner side of the vertical slab 19 and below the horizontal ledge 20 adjacent both said vertical slab 19 and horizontal ledge. An anchoring pin 22, slidably situated in a transverse opening 23 in the vertical slab 19 at a location adjacent the inner end of said vertical slab and opposite the horizontal ledge 20, includes a beveled inner end 24 and a rounded outer end 25. A fixing screw 26 in a threaded opening 27 in the inner end of the vertical slab 19, adjacent the horizontal ledge 20 and perpendicular to the anchoring pin 22, is adapted to be turned down against the beveled inner end 24 of said anchoring pin thus to cause the anchoring pin to be forcibly moved outwardly of the transverse opening 23. The horizontal ledge 20 includes an arcuate surface 28 at the side of said horizontal ledge opposite the vertical slab 19, and the anchoring pin 22 is situated at the side of said upper entity of the anchor 16 directly opposite said arcuate surface 28. The construction and arrangement and the overall dimensions in horizontal direction of the upper entity of said anchor 16 are such that the fixing

screw 26 can be turned down against the beveled inner end 24 of the anchoring pin 22 to cause the arcuate surface 28 of the horizontal ledge 20 and the rounded outer end 25 of said anchoring pin to be pressingly engaged against diametrically opposite portions of the internal cylindrical surface of a cylinder such as 12, about as disclosed in Fig. 3 of the drawings, thus to cause said upper entity of the anchor 16 to be grasped within the cylinder against the possibility of accidental displacement.

A lower entity of said anchor 16 is constituted as an L-shape piece of metal or material providing a vertical arm 29 and a horizontal lug 30 integral with a lower portion of said vertical arm 29 and adapted to be engaged beneath and against the lower surface of a cylinder block adjacent the lower end of a cylinder such as 12 in which the anchor 16 is situated, about as disclosed in Fig. 3 of the drawings. The upper portion of the vertical arm 29 of the L-shape piece of metal or material constituting the lower entity of the anchor 16 is situated between the spaced ears 21, 21 of the upper entity of said anchor 16 and the upper end of said vertical arm 29 is pivotally secured, as at 31, to said spaced ears 21, 21 for swinging movement in a vertical plane in direction toward and away from a portion of the cylinder wall directly below the arcuate surface 28 of the horizontal ledge 20. A compression spring 32, seated in a concavity 33 in a lower portion of the vertical slab 19 and engaged, as at 34, against a portion of the surface of the vertical arm 29 below the pivotal support 31 and opposite the horizontal lug 30, normally urges said vertical arm 29 to swing in direction away from said vertical slab 19 and toward the adjacent portion of the cylinder wall thus to cause said horizontal lug 30 normally to be situated beneath the lower surface of the cylinder block. Clearance is provided between the vertical slab 19 and the vertical arm 29 so that said vertical arm can be swung, against action of the compression spring 32, far enough away from said adjacent portion of the cylinder wall to permit the horizontal lug 30 to be moved from position beneath the cylinder block when this is intentional.

The clamp 17 includes a frame consisting of spaced apart, parallel, oppositely disposed frame members, denoted 35 and 36, respectively, secured to each other by transverse pins 37. Each of the frame members 35 and 36 includes an inwardly extending shelf, designated 38 and 39, respectively, at the lower portion of the corresponding frame member. Said shelves 38 and 39 are in the same horizontal plane, and the interior surfaces, represented 40 and 41, respectively, of the shelves 38 and 39 terminate in spaced apart, parallel relation, about as disclosed in Figs. 2 and 3 of the drawings. The frame members 35 and 36 are adapted to be situated within the rectilinear open area 14 of the base such as 10 of a cylinder boring machine and supported upon a cylinder block such as 11, and the bodies of said frame members are adapted to lie in spaced, substantially parallel relation to the spaced walls such as 13, 13 of said base.

Actuating cams, denoted 42 and 43, respectively, of the clamp 17 are supported upon an adjusting rod 44 of said clamp in such manner that said actuating cams can be moved toward and away from each other. More explicitly, the adjusting rod 44 includes threaded portions, one right and the other left, represented 45 and 46, respectively, upon its opposite ends, and the ac-

tuating cams 42 and 43 include internal threads ridable upon said opposite threaded portions 45 and 46. The adjusting rod 44 and said actuating cams 42 and 43 are situated between the frame members 35 and 36 of the clamp 17, and the overall width of each actuating cam is as disclosed but a trifle less than the measurement representing the distance between said frame members 35 and 36. A knurled hand piece 47 upon an end of said adjusting rod 44 and situated at position to be accessible is adapted manually to be turned thus to cause the adjusting rod 44 to be rotated.

The opposite end portions of spaced apart supporting rollers, denoted 48, 48, 48, 48, for the actuating cams 42 and 43 are rotatably mounted, as at 49, in the spaced walls 13, 13 of the base 10. Said supporting rollers are situated below said actuating cams, and each actuating cam includes a lower flat surface 50 supported, or adapted to be supported, upon supporting rollers 48 at the corresponding end of the clamp. The outermost supporting rollers 48 lie in cut-out portions 51 in the ends of the frame members 35 and 36, and the intermediate supporting rollers 48 extend through elongated slots 52 through said frame members 35 and 36.

Camming rollers, designated 53 and 54, respectively, of the clamp 17 are situated above the actuating cams 42 and 43. More explicitly, there is a camming roller 53 adjacent one end of the clamp frame directly above the actuating cam 42 and rotatably mounted upon a spindle 55 between and supported by the frame members 35 and 36, and there is a camming roller 54 adjacent the opposite end of said clamp frame directly above the actuating cam 43 and rotatably mounted upon a spindle 56 between and supported by said frame members 35 and 36. Said actuating cam 42 includes a camming surface 57 at its inner, upper portion adapted to be engaged under and against the camming roller 53, and said actuating cam 43 includes a camming surface 58 at its inner, upper portion adapted to be engaged under and against the camming roller 54.

The construction and arrangement are such that when the knurled hand piece 47 is turned to cause the adjusting rod 44 to be rotated the actuating cams 42 and 43 are moved inwardly or outwardly, as the case may be, upon said adjusting rod. Clearly, rotation of said actuating cams will be precluded by engagement of the lower flat surfaces 50, 50 with the supporting rollers 48, 48, 48, 48 and of the camming surfaces 57, 58 with the camming rollers 53, 54. The construction and arrangement are also such that when the actuating cams 42 and 43 are moved toward each other, the camming surfaces 57 and 58 will cause the camming rollers 53 and 54, and hence the clamp frame, to be elevated, and that when said actuating cams 42 and 43 are moved away from each other, said camming surfaces 57 and 58 will permit said camming rollers 53 and 54, and hence said clamp frame, to be lowered, until rested upon the cylinder block. Obviously, the cut-out portions 51, 51 and the elongated slots 52, 52 in the frame members 35 and 36 are for allowing movement of the clamp frame relative to the supporting rollers.

The connector 18 is constituted as a vertical retaining screw 59 situated in an internal thread 60 of the horizontal ledge 20 of the upper entity of the anchor 16 and having a horizontal annular flange or head 61 upon its upper end. An

upper portion of the vertical retaining screw 59, beneath the horizontal annular flange or head 61, is adapted to lie in the space between the interior surfaces 40 and 41 of the shelves 38 and 39 of the frame members 35 and 36, and portions 62 of the lower surface of said horizontal annular flange or head 61 are adapted to be engaged against portions of the upper surfaces of said shelves 38 and 39, about as disclosed in Fig. 2.

In Fig. 3 of the drawings the clamp frame is disclosed as resting upon the cylinder block 11, and the actuating cams 42 and 43 are disclosed as when at substantially released positions. It will be evident that when the knurled hand piece 47 is turned to cause said actuating cams 42 and 43 to be moved toward each other from their positions as in said Fig. 3, said clamp frame will become elevated, toward the position as in Fig. 2, thus to cause the shelves 38 and 39 to be grippingly engaged up against the lower surface of the horizontal annular flange or head 61 upon the vertical retaining screw 59. In practice, the connector 18 will be initially adjusted so that its annular flange or head 61 is set at close relation to or in contiguous relation with the upper surfaces of the shelves 38 and 39. Upon turning of the knurled hand piece 47 in direction to cause the actuating cams 42 and 43 to be moved toward each other, the lower flat surfaces 50, 50 will ride inwardly over the supporting rollers 48, 48, 48, 48 and the camming surfaces 57, 58 will ride inwardly under the camming rollers 53, 54, thus to cause the clamp frame to be elevated and the base 10 of the cylinder boring machine to be securely anchored to and clamped down upon the cylinder block 11. The horizontal lug 30 of course will preclude upward movement of the anchor 16, and said base 10 will be rigidly held to said anchor 16 and down against the cylinder block 11 through the instrumentality of the supporting rollers 48, 48, 48, 48, the actuating cams 42, 43, the camming rollers 53, 54, the spindles 55, 56, the frame members 35, 36, their shelves 38, 39 and the connector 18.

The set positions of the actuating cams 42 and 43 upon the adjusting rod 44 may be steadied by a tension spring 63.

Plugs 64 in one of the walls 13 of the base 10 may constitute means for removably retaining the supporting rollers 48, 48, 48, 48 in their intended positions. Evidently, removal of said supporting rollers from the spaced walls 13, 13 of said base 10 will permit removal of the clamp 17 from the rectangular open area 14.

Clearly, the anchor 16 will be readily and easily removable from a cylinder upon release of the anchoring pin 22 by partial withdrawal of the fixing screw 26.

What is claimed is:

1. In an attachment device for fastening a machine base upon and against a surface of a block, a member adapted to be anchored to said block, spaced apart supporting elements upon said machine base adapted to be engaged against a surface of said block, a clamp frame adapted to be connected to said member, spaced apart camming elements upon said clamp frame, and spaced apart actuating cams upon said supporting elements adapted to be actuated to cause said camming elements to be moved in direction away from said block.

2. In an attachment device for fastening a machine base upon and against a surface of a

block, a member adapted to be anchored to said block, spaced apart supporting elements upon said machine base adapted to be engaged against a surface of said block, a clamp frame, means for connecting said clamp frame to said member, spaced apart camming elements, and spaced apart actuating cams adapted to be actuated to cause said camming elements to be moved in direction away from said block thus to cause said spaced apart supporting elements to be engaged under pressure against said surface.

3. In an attachment device for fastening a machine base upon and against a surface of a block, a member adapted to be anchored to said block, spaced apart supporting rollers upon said machine base, a clamp frame adapted to be connected to said member, spaced apart camming rollers upon said clamp frame, and spaced apart actuating cams upon said supporting rollers adapted to be actuated to cause said camming rollers selectively to be moved while substantially in a single plane away from said block and to be permitted to be moved by gravity toward said block.

4. In an attachment device for fastening a machine base upon and against a surface of a block, a member adapted to be anchored to said block, spaced apart supporting rollers upon said machine base, a clamp frame, means for connecting said clamp frame to said member, spaced apart camming rollers upon said clamp frame, and spaced apart actuating cams adapted to be actuated to cause said camming rollers selectively to be moved while substantially in a single plane away from said block and to be permitted to be moved by gravity toward said block.

5. In an attachment device for fastening a machine base upon and against a surface of a block, a member adapted to be anchored to said block, spaced apart supporting elements upon said machine base, a clamp frame, means for connecting said clamp frame to said member, spaced apart camming elements upon said clamp frame, and spaced apart actuating cams adapted to be actuated to cause said camming elements to be moved relative to said spaced apart supporting elements.

6. In an attachment device for fastening spaced apart walls of a machine base upon and against a surface of a block, a member adapted to be anchored to said block, spaced apart supporting elements upon said machine base between its spaced apart walls, a clamp frame between said spaced apart walls of said machine base, means for connecting said clamp frame to said member, spaced apart camming elements upon said clamp frame, and spaced apart actuating cams adapted to be actuated to cause said camming elements to be moved in direction away from said block.

7. In an attachment device for fastening spaced apart walls of a machine base upon and against a surface of a block, a member adapted to be anchored to said block, spaced apart supporting elements upon said machine base between its spaced apart walls, a clamp frame between said spaced apart walls of said machine base, means for connecting said clamp frame to said member, spaced apart camming elements upon said clamp frame, and spaced apart actuating means upon said supporting elements adapted to be actuated to cause said camming elements to be moved in direction away from said block.

8. In an attachment device for fastening spaced apart walls of a machine base upon and

against a surface of a block, a member adapted to be anchored to said block, spaced apart supporting rollers upon said machine base between its spaced apart walls, a clamp frame between said spaced apart walls of said machine base, means for connecting said clamp frame to said member, spaced apart camming rollers upon said clamp frame, and spaced apart actuating cams adapted to be actuated to cause said camming rollers selectively to be moved away from said block and to be permitted to move by gravity toward said block.

9. In an attachment device for fastening spaced apart walls of a machine base upon and against a surface of a block, a member adapted to be anchored to said block, spaced apart supporting elements upon said machine base between its spaced apart walls, a clamp frame between

said spaced apart walls of said machine base, means for connecting said clamp frame to said member, spaced apart camming elements upon said clamp frame, and spaced apart actuating cams adapted to be actuated to cause said camming elements to be moved in direction away from said block.
